DESIGN FOR A DISPENSER FOR INTER-FOLDED SHEETS

Frank L. Broeren, Neenah, Byron T. Hoffmaster, Menasha, and Archie S. Krueger, Green Bay, Wis., assignors to Marathon Paper Mills Company, Rothschild, Wis., a corporation of Wisconsin

Application January 3, 1938, Serial No. 74,044

Term of patent 14 years

To all whom it may concern:

Be it known that Frank L. Broeren, Byron T. Hoffmaster, and Archie S. Krueger, citizens of the United States, residing, respectively, at Neenah, Winnebago County, Menasha, Winnebago County, and Green Bay, Brown County, in the State of Wisconsin, have invented a new, original, and ornamental Design for a Dispenser for Interfolded Sheets, of which the following is a specification, reference being had to the accompanying drawing, forming a part thereof.

Figure 1 is a perspective view of the dispenser for interfolded sheets showing our design.

Figure 2 is a side elevational view of the dispenser.

Figure 3 is a front elevational view of the dispenser.

We claim:

The ornamental design for a dispenser for interfolded sheets, as shown.
